METAL DOOR.

Application filed February 25, 1922. Serial No. 539,164.

This invention relates to metal doors, and more particularly to the construction of frame-members for such doors.

The stiles and rails of metal doors of usual construction comprise a simple deep channel piece, to the open margins of which are affixed panel engaging moldings. Numerous types of moldings have been employed, and different means for securing them to the stiles or rails, but the results have not been altogether satisfactory. Moreover with stiles or rails comprising sheet metal channels, it is desirable to reinforce and hold in spaced relation the open margins of the channels.

The principal object of this invention is, therefore, to provide in a sheet metal frame-member for doors comprising a channel shaped body-portion, an improved member to connect together and reinforce the margins and also to provide simple rectilinear slots within and parallel with the sides of the frame member for securing the panel engaging moldings to the body-portion of the frame-member.

In previous constructions there have been employed clamping members to hold together the moldings and body-portions comprising the rails or stiles, which clamping members were so arranged as to require that they be slid longitudinally into place after the moldings had been positioned on the body-portions, thus encountering considerable frictional resistance to being set in place.

A further object of the invention is therefore to provide a retaining member which may be inserted transversely into place in the body portion of the frame member and fastened thereto, thereby avoiding the frictional resistance aforesaid, and which will, when so fastened, provide rectilinear slots to permit movement transversely of the molding to sheath the molding margins.

Still another object of the invention is to provide a retaining member suitable for retaining in position moldings comprising either one or a plurality of parts.

The invention will be more readily understood by reference to the accompanying drawing illustrating one embodiment thereof, and in which:

Fig. 1 is a perspective view of a section of one door frame-member, and

Fig. 2 is a sectional view of the invention applied to a modified frame-member. 55

Fig. 3 is a view partly in section of a door prior to assembly.

Fig. 4 is an elevation of the completed door.

Fig. 5 is a section on line 5—5 of Fig. 3. 60

Fig. 6 is a section on line 6—6 of Fig. 3.

In Fig. 1 there is shown a channel-shaped member 1 composed of a single piece of sheet metal having an edge plate and parallel side walls and comprising the body-portion of a 65 rail or stile frame-member. The upper margins of the channel-shaped member are inturned at 2, these inturned portions being further bent to provide reversely extending marginal portions 3. While the particular 70 angle between the portions 2 and the side walls of the channel-shaped member is immaterial, the reversed portions 3 should be substantially parallel to each other, as will become apparent hereinafter. A one piece 75 molding 4 comprises a panel receiving portion 5, two ornamental side walls 6, each having a base portion 7 and two parallel marginal portions 8. The recess 5 is adapted to engage a panel 9 of any usual type, 80 but is particularly designed to hold an indestructible panel, such as one or more sheet metal plates with or without interstitial packing. As seen, the base portions 7 lie in the same plane and are adapted to rest upon 85 the portions 2 of the channel member 1. The margins 8 of molding 4 are spaced so as to overlie and be in frictional contact with the inner surfaces of margins 3 of the body-portion 1 of the frame-member. Thus in 90 assembling a door the molding is applied to the rail or stile 1 by a mere transverse movement, no movement longitudinally of the molding or body-portion being required.

While there is some friction between portions 7 and 8 of the molding and portions 2 and 3 of the body, such engagement would not be sufficient to positively prevent a relative movement therebetween, nor would the structure as thus far described be sufficiently 100 strong to withstand ordinary wear and tear. In order to further secure the molding to its body-portion, there is therefore provided a transversely-disposed retaining member 10 which is bent intermediate its opposite edges 105 to provide a channel portion having parallel

side walls 11 whose outer surfaces are spaced to abut against or frictionally engage the inner surfaces of margins 8 of the molding when the same are inserted within the rectilinear longitudinally disposed slot formed by bending the reverse portions 12 to lie in parallel planes. Said reverse portions are spaced to abut against or frictionally engage the outer surfaces of reverse margins 3 of the body-portion, so that the seat for the marginal flanges 8 of the molding is between said reverse margins 3 of the body-portion and the walls 11 of the channel portion of the retaining member. The said retaining member further comprises two lateral extensions 13 of sufficient length to span the inside clearance between the reverse margins 3 and the side walls of the body-portion 1 of the frame-member. The retaining-member is thus seen to consist of a plate having two rectilinear grooves comprising the substantially parallel side walls 11 and 12, the portions 10 and 13 being the main plate portions, since these latter portions might lie in the same plane without departing from the spirit of the invention. Owing to the parallelism of the side walls of the grooves in the retaining-member and to the fact that the entrance to these grooves is unobstructed by the web portion uniting them, it will be seen that the retaining-member may be set in place by a purely transverse movement, unlike previous clamping-members which had to be forced longitudinally of the molding and body-portions after their assembly. Moreover, the retaining-member is preferably placed in operative relation and fastened to the body-portion before connection to the molding, thus forming independent frame-members or units having rectilinear grooves in one edge. In any case, the retaining-member is most desirably permanently secured to the body-portion, most advantageously by spot welds uniting surfaces 2 and 13. Where still greater strength is required the margins 14 of the retaining-member may be bent to lie in frictional contact with the side walls of body-portion 1, but such portions 14 are not an essential of the invention. In case such marginal portions are provided, they may, if desired, be welded to the side walls.

In Fig. 2 there is shown a modified molding comprising a main portion 15 having parallel lower margins 8 identical with those of molding 4, also provided with a portion 5 to support a panel. This type of molding is provided for use with panels of glass or other relatively fragile material which is subject to replacement, and while the frame-member construction is substantially identical with that described for the modification shown in Fig. 1 it is seen that molding 15 does not hold both edges of panel 9. There is therefore provided an additional

strip 16 which may be removably secured to molding 15 as by screws 17. The retaining-member 10 is in every respect the same as that employed with the other modification, so that but one type of body-portion 70 1 and retaining-member need be assembled and carried in stock in order that frame-members for doors having either fixed panels or removable panels may be constructed upon short notice. 75

The employment of the elements thus far described in constructing moldings, such as shown in the drawings, gives a sufficiently strong and rigid structure for doors of small or medium size, up to seven feet in length 80 for example, when the rails and stiles are merely united at the four corners of the door in any conventional manner. For example we may, as illustrated in Figs. 3 and 5, fit within and between the inner surfaces of 85 the opposite side walls of the top and bottom rails horizontal channels 15 having extension ends 15^a which extend into and fit between the side walls of the stiles and we may also provide vertical spanning channel 90 members 16 extending partially within the rail members also fitting, when the parts are brought together in assembly, between the side walls of the stiles, the marginal portions 2 and 3 of the body portions of the 95 stile frame members and the retaining member portions being cut away at the corners of the door as at 17 to permit insertion of the parts 15^a and 16, which are fastened to stile and rail by any well known method 100 such as spot welding. With larger doors or those subject to severe conditions in use, there may be, however, some tendency for the molding to be drawn away from the retaining member. In order to absolutely 105 prevent this, there are most desirably provided a suitable number of locking members 18, each comprising a straight sided pin, and made by cutting off lengths of small wire rod. After the channels 1, retaining-members 10 and moldings have been assembled, 110 holes for pins 18 are drilled through one wall of the channel 1, the adjacent marginal portion 14 of the retaining member—if such portion is employed—the side walls 11 and 12 of both grooves of the retaining member, the marginal portions 3 and 8 of the channel and molding, respectively. These holes are drilled at suitable distances, such as every 115 two feet, and, it is to be noted, do not extend through the marginal portion 14 and side wall of the channel 1 on the side of the channel opposite to that in which drilling of the holes commenced. By making all the pins 18 of uniform length such that, when 120 the inner end is forced into contact with the inner surface of the farther margin 14 of the retaining-member, the head of the pin 125 will be flush with the outer surface of the side wall of channel 1 through which the 130

pin was inserted, the pins are rendered practically invisible in the finished article. In order to anchor each pin, its head is most desirably united as by spot welding to the 5 side wall of channel 1 which it pierces.

While the invention has been described in connection with two particular forms of panel engaging molding, it is obvious that numerous departures from the structure described 10 might be made without in any case departing from the spirit of the invention as set forth in the appended claims.

What is claimed is:

1. A sheet metal door embodying a panel, 15 a panel molding having integral and spaced rectilinear marginal flanges extending parallel with the surfaces of said panel on opposite sides thereof, and hollow stile and rail frame-members, each substantially rectangular in cross-section and having in one edge spaced rectilinear slots extending in the same direction as said molding flanges and forming 20 seats for sheathing said flanges by a relative transverse movement of said frame member and said molding.

2. A sheet metal door embodying a panel, 25 a panel molding having integral and spaced rectilinear marginal flanges extending parallel with the surfaces of said panel on opposite sides thereof, and hollow stile and rail frame-members, each substantially rectangular in cross-section and having in one edge spaced rectilinear slots extending in the same direction as said molding flanges 30 and forming seats for sheathing said flanges by a relative transverse movement of said frame member and said molding, and means for uniting the rails and stiles at the four corners of the door to retain all the parts 40 of the door together.

3. A sheet metal door embodying a panel, 45 a panel molding having integral and spaced rectilinear marginal flanges extending parallel with the surfaces of said panel on opposite sides thereof, and hollow stile and rail frame-members, each substantially rectangular in cross-section and having in one edge spaced rectilinear slots extending in the same direction as said molding flanges and 50 forming seats for sheathing said flanges by a relative transverse movement of said frame member and said molding, means for uniting the rails and stiles at the four corners of the door to retain all the parts of the door together and a pin passing transversely 55 through one of the walls of said frame member and through said groove walls and molding flanges to more securely lock the molding, frame members and panel together.

60 4. A sheet metal door embodying a panel, 65 a panel molding having integral and spaced rectilinear marginal flanges extending parallel with the surfaces of said panel on opposite sides thereof, and separable stile and rail frame-members, each comprising a body-

portion having side plates provided with spaced parallel marginal portions and a retaining member arranged across the space between the marginal portions of said body-portion and fastened to the free margins 70 of the said side plates thereof, to produce a hollow member substantially rectangular in cross-section, said retaining member having spaced rectilinear grooves extending in the same direction as said molding flanges 75 and forming seats for sheathing said flanges by a relative transverse movement of said frame-member and said molding, and means for retaining said frame-members and panel moldings together.

5. A sheet metal door embodying a panel, 80 a panel molding having integral and spaced rectilinear marginal flanges extending parallel with the surfaces of said panel on opposite sides thereof, stile and rail frame-members independent of each other and each comprising a channel-shaped body-portion formed of a single piece of sheet metal having an edge plate and spaced parallel side walls provided with free parallel marginal flanges and a retaining member arranged across the space between and fastened to the marginal flanges of said channel-shaped body-portion to form a substantially rectangular, tubular unit, said retaining member 85 having spaced longitudinally disposed rectilinear grooves forming seats for sheathing said molding flanges by a relative transverse movement of the frame members and said molding.

6. A sheet metal door embodying a panel, 90 a panel molding having integral and spaced rectilinear marginal flanges extending parallel with the surfaces of said panel on opposite sides thereof, stile and rail frame-members independent of each other and each comprising a channel-shaped body-portion formed of a single piece of sheet metal having an edge plate and spaced parallel side walls and provided with inturned portions and reversely extending margins arranged to provide an open edge provided with free parallel marginal flanges and a retaining member arranged across the space between and fastened to the marginal flanges of said channel shaped body-portion to form a substantially rectangular, tubular unit, said retaining member having spaced longitudinally disposed rectilinear grooves fitting over said reversely extending margins of the frame-member and also forming seats for sheathing said molding flanges by a relative transverse movement of the frame-members and said molding.

7. A sheet metal door embodying a panel, 125 a panel molding having integral and spaced rectilinear marginal flanges extending parallel with the surfaces of said panel on opposite sides thereof, stile and rail frame-members, each comprising a channel-shaped 130

body-portion formed of a single piece of sheet metal having an edge plate and parallel side walls and provided with inturned portions and reversely-extending marginal portions, extending parallel with said molding flanges and a retaining member arranged across the open edge of said channel member and having spaced grooves fitting over said reversely-extending margins of the body portion, said grooves also forming seats for sheathing said molding flanges by movement of the frame-members transversely of said molding, said retaining-member also having between said grooves an inverted channel portion for holding the inner walls of the grooves in spaced relationship from each other and in frictional engagement with the molding flanges, and also being provided with lateral portions on the outer sides of said grooves extending into abutment with the outer surface of the side walls and holding the outer walls of said grooves in spaced relationship from the side walls of the channel-shaped member and in frictional engagement with said reverse margins.

8. A sheet metal door embodying a panel, a panel molding having integral and spaced rectilinear marginal flanges extending parallel with the surfaces of said panel on opposite sides thereof, stile and rail frame-members, each comprising a hollow unit, substantially rectangular in cross-section formed of a channel-shaped body-portion having side walls and parallel marginal portions and a retaining member to connect the free margins of the said side walls together, said retaining member having longitudinally disposed rectilinear grooves extending in the same direction as said molding flanges and forming seats for sheathing said molding flanges by a movement of the frame-member transversely of said molding, and a pin for fastening each frame-member to a molding, said pin passing transversely through one of the side walls of said channel-shaped body-portion, through the walls of the said grooves, and through said molding margins. 40
